J. W. NASMITH

COMBING MACHINE

Filed March 30, 1922

UNITED STATES PATENT OFFICE.

JOHN WILLIAM NASMITH, OF MANCHESTER, ENGLAND.

COMBING MACHINE.

Application filed March 30, 1922. Serial No. 548,209.

To all whom it may concern:

Be it known that I, JOHN WILLIAM NASMITH, a subject of the King of Great Britain, residing at Manchester, in the county 6 of Lancaster, England, have invented a new and useful Combing Machine, of which the following is a specification.

In Nasmith and other combing machines the feeding of the material is usually performed by a feed roller carried in the nipper and resting on the bottom nipper plate or dish or on a second roller and during the forward movement of the nipper the roller is caused to turn and feed the necessary amount 15 of material forward each stroke during the detaching period. During the detaching operation a considerable amount of long fibre, which is not carried forward by the detaching rollers, is drawn out of the nippers and 20 crumpled up behind the top comb and, not being held by the nipper when it closes, is carried away as waste.

The first object of the present invention is to save this unnecessary waste by causing 25 the feed apparatus to draw back a short length of the previously fed material within the nipper as it commences to recede from the detaching roller and before it closes and this may be conveniently done by employing 30 a secondary or feed nipper in place of the usual roller although a roller may be caused to give the desired result.

Usually the feed organ has to be adjusted separately in each head of the machine 35 to suit the material being combed and the amount of waste required to be taken out. The lip of the nipper when in its most forward position is set nearest the detaching roller for short material and low waste and 40 farther away for long fibres and greater waste. And as it carries the feed organ with it the distance between the latter and the detaching roller is correspondingly altered when any alteration is made in the 45 position of the nipper. But it is desirable that in addition to this the position of the feed organ within the nipper should also be changed. The farther the nipper is set back from the detaching roller the farther 50 the feed organ should be set back from the lip of the nipper and vice versa, thus the feed organ should be displaced not only the amount the nipper is moved but a further amount in the same direction.

55 A second object of the present invention is therefore to so arrange matters that as

the nipper is withdrawn farther from the detaching roller, the feed organ, carried by the nipper shall be simultaneously and automatically withdrawn farther from the lip 60 of the nipper so that its distance from the detaching rollers is not only increased by the distance the nipper has been set back but by an additional amount.

The manner in which these two objects 65 are achieved will now be described in detail with reference to the drawings in which

Fig. 1 represents a section through one head of the nipper of a Nasmith combing machine showing the feed nipper when the 70 main nipper is in its position at the rear-most end of its stroke, the upper jaw of the main nipper being omitted.

Fig. 2 shows the same when the main nipper is in its most forward position and with 75 the addition of the parts for operating the feed nipper.

Fig. 3 shows a feed roller and means of operating it as required by this invention.

Figure 4 is a view showing the main nipper just about to close when it has receded some distance from the detaching roller and the feed nipper, within the main nipper, just as it begins to open after having drawn 85 the material away from behind the top comb and back into the main nipper, the upper jaw of the latter and the top comb being represented.

Referring first to Fig. 2, the combing cylinder is represented by 1, the detaching roller by D and the nipper shaft by W. To avoid unnecessary complication of the drawing the connection between this shaft and the nipper is not shown but may be seen in the drawing 90 appended to my United States Patent No. 1,369,532. The rocking of this shaft swings the nipper cheeks N² (one at either end of the nipper) the nipper bridge B and the lower jaw P² uninterruptedly to and fro between the position shown in Fig. 1 to that shown in Fig. 2 that is between the dotted radii C' and C along the dotted arc C². Fixed in the nipper cheeks N² are studs 16 upon which pivot freely bell crank levers L. 95 To the extremity of the long arm of the levers L are freely pivoted at 33 links 34 whose upper ends are adjustably secured to blocks 36 swivelling in projections 11 cast on the levers 9 keyed on the shaft 10. Pivoted at 32 to the short arm of the levers L 100 are arms 31 carrying the lower jaw of the 110

feed nipper, F. Each arm 31 carries a bowl 30 running on ledges 35 formed on the nipper cheeks N² for the purpose of keeping the jaw F clear of the nipper plate P². As the 5 nipper swings to and fro it carries with it the studs 16 on which the levers L are freely pivoted, but the pins 33 cannot partake of this motion owing to the links 34, attached to the fixed swivels 36 and the levers L therefore turn on the studs 16 causing the arms 31 and the lower jaw F to move to and fro within the main nipper running on the bowl 30. The arms 37, carrying the upper jaw F' of the feed nipper also move to and 10 fro with the arms 31 being pivoted thereon at 38. Pivoted to arms 37 at the point 39 is the link 40 having fixed in its upper end a screwed stud 40^a carrying loose upon it the open spring 44 and passing freely through the block 41 which swivels freely in the end 15 of the lever 42 keyed on the shaft T³. The upper end of the stud 40^a is threaded to receive adjusting nuts 43.

A pin 48 is fixed in the framing of the 20 machine and on it swings a lever 47, the outer end of which carries a stud on which is a bowl 49 resting on a suitably shaped cam M (shown dotted in Fig. 2). A link 46 connects the lever 47 to the lever 45 also 25 keyed on the shaft T³. One end of a spring 50 is attached to the end of the lever 45 and the other end to a stud 51 fixed to the framing of the machine and the spring being always in tension the bowl 49 is constantly 30 kept in contact with the contour of the cam M which in rotating suitably rocks the shaft T³ to open and close the jaws F, F' of the feed nipper at the appropriate time and nipping the material with a spring pressure 35 through the spring 44. The shape of the cam M in combination with the nuts 43 regulates the time when the feed nipper opens and closes and consequently the amount of feed and the cam is so shaped that it closes the feed nipper jaw F' when it has advanced 40 a certain distance from the position shown in Fig. 1 towards that shown in Fig. 2 and keeps it closed until the main nipper, whose lower jaw is designated P², has receded some 45 distance from the detaching roller on the return stroke and as during this time the feed nipper has also executed a small part of its retrograde movement within the main nipper, still gripping the material, it withdraws part of the previously fed material 50 back again within the main nipper.

Fig. 4 shows the various organs approximately in their relative positions just as the feed nipper F' is opening after it has taken back with it, in its retrograde movement in 60 relation to the lower nipper jaw P², a certain length of the lap (shown at 52), which it has drawn back away from behind the top comb T as shown at 53. At this point the top nipper jaw P³ is about to close on

the lower jaw P² which has travelled some distance towards the position shown in Fig. 2, and grip the lap 53 to hold it whilst the cylinder needles comb the projecting tuft. At the same time the feed nipper jaws F', F open and they continue their retrograde movement in relation to the nipper jaw P² and move further up the lap, now held by the jaws P², P³, ready to take a fresh grip on the next forward stroke. To allow for 70 this the feed nipper is caused to close sufficiently early on the forward stroke to feed as much material as is required each stroke plus the amount that is again to be withdrawn within the main nipper on its return 80 stroke before it closes to hold the material during combing by the cylinder.

When the requisite amount has been drawn back into the main nipper the feed nipper is opened by the cam M and moves back up 85 the lap of material ready to take a fresh grip farther up on the next forward movement as seen in Fig. 1.

By means of the adjusting nuts at the upper end of the link 34 the position of the to 90 and fro movement of the feed nipper in relation to the lip of the main nipper jaw P² can be regulated, that is to say it can be caused to move to and fro near the lip of the main nipper for short fibres and fur- 95 ther away for long fibres.

In my United States Patent No. 1,369,532 it is shown how the shaft 10 is used to regulate the distance between the lip of the nipper plate P² and the detaching roller D. 100 This distance is varied in practice according to the length of the fibres being combed and the amount of waste to be taken out. Generally the shorter the fibre and the less the waste the nearer P² must approach to D and the longer the fibre and the greater the waste the less near it must approach. This is also what is required of the feed organ, and by connecting the link 34 to an arm 11 on the setting lever 9, any adjustment of the nipper by means of the lever 9 simultaneously and automatically produces a corresponding change in the same direction of the feed 110 nipper within the main nipper. For if all the feed nippers F be set in line and to a 115 desired distance from the lip of the main nipper P² by means of the nuts 12, it follows that if the shaft 10 be moved somewhat counter clockwise the pivot 36 will be depressed and the lever L turned on the stud 16 drawing the feed nipper F further from the lip of the main nipper P² and vice versa, whilst the same movement of the shaft 10 alters the distance between the lip of the main 120 nipper and the detaching roller D. A convenient combined adjustment of the main nipper to the detaching roller and simultaneously of the feed nipper within the main nipper is thus obtained.

In Fig. 3 means are shown whereby a feed 130

roller may be operated to feed a certain amount of material on the forward stroke and then withdraw a small amount on the return stroke. But as in this case the axis 5 of the roller remains fixed in relation to the main nipper jaw P^2 , each roller must be adjusted separately in relation to the main nipper when any change is required. On the 10 end of the feed roller is a toothed pinion P . A toothed sector S , whose centre is at N when in gear with the pinion P , is hinged on a stud 38^a which is fixed on a convenient part 15 of the framing of the machine. Pivoted at 39^a on the sector S is the link 40, connected as in Fig. 2 to the lever 42 which is operated by a suitably shaped cam M so that on the forward stroke of the nipper the sector S is dropped into gear with the pinion P to turn the roller forward and left in gear until the 20 main nipper has receded some distance from the detaching roller on the return stroke and turned the roller slightly backwards to withdraw a short length of the previously fed material again within the nipper before it 25 closes.

Although the drawings show and the specification describes the invention applied to a combing machine constructed according to my United States Patent No. 30 1,369,532 it will be understood that such a feed mechanism may be equally well applied to other similar types of combing machines. No claim is herein made to the specific form 35 of the invention illustrated in Figure 3, as the same forms the subject matter of a divisional application Serial No. 613,203.

What I claim and desire to secure by Letters Patent is:—

40 1. In a combing machine of the Nasmith type the use of feed apparatus designed to

draw away from the top comb and into the nipper a short length of the previously fed material as the nipper commences to recede from the detaching roller as the detaching process is completed and before the nipper 45 closes on the material to hold it whilst the cylinder combs the projecting tuft.

2. In a combing machine a feed nipper operating within the main nipper, the said feed nipper comprising a lower jaw adapted 50 to move back and forth within the main nipper as it swings, a top jaw moving back and forth with the lower jaw and means for opening and closing the said upper jaw, the said means being such as to close the upper 55 jaw during the forward swing of the main nipper to feed a given amount of material forward and keep it closed until a part of the backward swing has taken place and withdrawn again within the main nipper 60 a part of the previously fed material.

3. In a combing machine a feed nipper operating within the main nipper, the said feed nipper comprising an upper and lower jaw adapted to move back and forth within the main nipper, means for opening and closing the jaws of the feed nipper at the appropriate time, and means for varying the position of each feed nipper in relation to the lip of the main nipper to suit the length 70 of fiber to be combed, combined with means whereby the position of the feed nipper within the main nipper is automatically and simultaneously altered whenever the position of the main nipper in relation to the detaching roller is changed.

In testimony whereof I have affixed my signature.

JOHN WILLIAM NASMITH.
